CURTAIN AND SHADE FIXTURE

Filed Feb. 7, 1928

UNITED STATES PATENT OFFICE

WALTER R. SCOTT, OF WASHINGTON, PENNSYLVANIA

CURTAIN AND SHADE FIXTURE

Application filed February 7, 1928. Serial No. 252,590.

The present invention relates to curtain and shade fixtures, and the primary object of the invention is to provide a combined curtain and shade fixture which may be readily applied to various width of window casings without the use of screws or nails.

A further object of the invention is to provide a combined curtain and shade fixture embodying extensible sections one of which is adjustable to accommodate itself to windows of various widths, with the companion member being extensible for accommodating shade rollers of various lengths.

A further object of the invention is to provide a combined curtain and shade support adapted to be clamped over the edges of a window casing and held in a rigid position against displacement thru raising and lowering of the shade.

A still further object of the invention is to provide a device of this character which is of extremely simple and durable construction, and one which may be readily attached to the window casing thru the employment of a screw driver.

Other objects and advantages of the invention will be apparent during the course of the following detailed description, taken in connection with the accompanying drawing, forming a part of this specification and in which drawing:

Figure 1 is a horizontal section thru a conventional type of window casing and showing one form of the improved curtain and shade fixture as applied to the side architraves of the window casing.

Figure 2 is an enlarged view partly in elevation and partly in section of the extensible tie member forming a support for the shade roller.

Figure 3 is an enlarged transverse section on line 3—3 of Figure 2.

Figure 4 is an enlarged transverse section on line 4—4 of Figure 2.

Figure 5 is an enlarged transverse section on line 5—5 of Figure 1 and looking in the direction of the arrows.

Figure 6 is a perspective view of the major bracket section of the extensible tie member.

Figure 7 is a perspective view of the minor

bracket section of the extensible tie member.

Figure 8 is a perspective view of one of the hanger or clamp bars as illustrated in Figure 1.

Figure 9 is a horizontal section thru a window casing and showing a slightly modified form of hanger or clamp bar for use in connection with relatively wide architraves or for use in disposing the edge of the curtain or drape inwardly of the edge of the architrave.

Figure 10 is a perspective view of the form of hanger or clamp bar as illustrated in Figure 9.

Referring to the drawing in detail, and wherein similar reference characters designate corresponding parts thruout the several views, the letter A designates a window casing, and B the improved combined curtain and shade fixture for supporting suitable curtains or drapes C and a conventional type of roller shade D at the window opening. The combined curtain and shade fixture embodies a pair of similarly formed hanger or clamp members 5 for supporting an extensible curtain rod 5', an adjustable tie member 6, and coupling means 7 adjustably connecting the hanger members 5 to opposite ends of the tie member 6.

The window casing A is of usual construction and embodies the side architraves 8 with which the opposite ends of the combined curtain and shade fixture are detachably associated.

Referring first to the specific construction of the hanger or clamp members 5, the same are of identical construction and are preferably formed from flat strips of metal shaped to form a main body portion 10 having an angular extension or arm 11 formed at its outer end. Extending to a like side as that of the arm 11 and at the inner end of the body portion 10 is a substantially V-shaped anchoring flange 12 which is intended to be forced into the plaster 9 behind the inner edge of the architrave 8 so that the hanger members extend horizontally with their inner surfaces engaging the outer edges of the architraves. As will be observed in Figure 1, when the hanger members 5 are in position

at opposite edges of the window casing, the angular arms 11 extend toward one another in spaced relation at the front faces of the architraves 8. Provided in the body portion of each of the members 5 are circular openings 13, and these openings 13 are spaced from the anchoring flanges 12 for a distance slightly greater than the thickness of the architraves 8.

10 The extensible curtain rod 5' embodies a pair of outer and inner telescoping sections 14 and 15 respectively which are adapted to receive the inturned extensions 11 as clearly illustrated in Figure 1. The inner section 15 may be enlarged at one end for receiving the angular extension of one of the hanger members. Thus it will be seen that the inturned angular extensions 11 act to receive the opposite ends of an extensible curtain rod which 20 may be adjusted to various widths of windows.

Referring now to the extensible tie member 6, the same embodies a hollow coupling section 16 which is of rectangular shape in cross section as clearly illustrated in Figures 3 and 4, and is provided adjacent each end with transversely aligning openings 17. This coupling section 16 is of a length less than the width of the smallest size window opening for which the combined curtain and shade fixture is intended to be used. Telescopically associated with one end of the coupling section 16 is a major bracket section 18 including an elongated shank portion 19 and an angularly offset bracket arm 20. The bracket section 18 is formed from a bar of metal of rectangular shape in cross section and is adapted to have its elongated shank portion 19 slidable into the hollow coupling section 16. The shank portion 19 is provided with a number of suitably spaced apart openings 21 which may be brought into alignment with the apertures 17 at one end of the coupling section for receiving a removable key 22 whereby the major bracket section is held against movement with respect to the coupling section as will readily be apparent. As will be observed in Figure 2, the shank portion 19 is of a length greater than that of the coupling section 16 and thus will permit of a wide range of adjustment. The bracket arm 20, adjacent its juncture with the shank portion 19 is provided with a round opening 23, and provided adjacent the outer end of the bracket arm, and opening at the upper edge thereof, is a rectangular shaped slot 24 for receiving the usual flattened trunnion of conventional type of shade rollers. The tie member further includes a minor bracket section 25 embodying a relatively short shank portion 26 for fitting into one open end of the coupling section 16, and an angularly offset bracket arm 27 provided adjacent its outer end with an opening 28 for receiving one end of the shade roller

D. The shank portion 26 is provided with a suitable opening 29 to align with the openings 17 at one end of the coupling section 16 and receive a suitable rivet or the like 30 for fixedly coupling the bracket section 25 to one end of the coupling section 16. The bracket arm 27 adjacent its inner end is provided with an opening 23' which preferably aligns axially with the opening 23 of the major bracket section when the bracket sections 18 and 25 are operatively connected with the coupling section 16.

The coupling means 7 for adjustably connecting the hanger members 5 to opposite ends of the tie member 6 embodies a pair of threaded bolts having their shank portions freely rotatable in the aligning openings of the hanger members and the bracket arms of the tie member. One of these bolts is provided for each end of the tie member, with the shank portion of one of the bolts extending thru the opening 13 of one of the hanger members and the opening 23 of the bracket arm 20, and the shank portion of the companion bolt extending thru the opening 13 of the opposite hanger member and the opening 23' of the bracket arm 27. Disposed inwardly of each bracket arm 20 and 27 is a nut 32 for threaded reception of the threaded inner ends of the bolts, and these nuts 32 are of a size such that one flat edge thereof engages the outer face of the shank portions of their respective bracket sections. Thus it will be seen that upon rotation of the bolts, the nuts 32 will be held against rotation and allow for the hanger members to be moved toward and away from their respective bracket arms upon rotation of the bolts. As will be observed in Figure 1, the bolts are provided with slotted heads 34 whereby the bolts may be readily turned by means of a screw driver or the like. It may here be well to state that when the fixture is in position upon the window casing, the inner flat surfaces of the shank portions 19 and 26 of the bracket sections 18 and 25 respectively, are in surface contact with the face sides of the architraves 8 and that the bracket arms 20 and 27 are held in a horizontal position and against movement during raising and lowering of the shade.

In mounting the improved fixture upon the window casing, and with the cotter pin 22 removed, the major bracket section 18 is adjusted longitudinally of the coupling section 16 so as to space the bracket arms 20 and 27 for properly receiving the trunnions of the shade roller D, after which the cotter pin 22 may be replaced to extend thru the proper opening 21 of the shank portion 19 for retaining the bracket arm in proper spaced relation. The anchoring flanges 12 of the hanger members may then be placed so that they may be drawn to positions behind the architraves 8, after which it is merely necessary to turn

the bolts by means of a screw driver for threading the bolts thru the nuts 32. This rotating of the bolts will draw the anchoring flanges 12 into positions behind the architraves and the hanger members into engagement with the outer edges of the architraves. As will be observed, the bolts extend relatively close to the faces of the architraves and thus there is little or no tendency of the hanger members to be drawn inwardly toward one another thru tightening of the coupling means. Thus it will be seen that the extensible member 6 aside from forming a support for the shade roller, acts as a tie member between the hanger members 5.

Referring particularly now to Figures 9 and 10, and wherein a slightly modified form of hanger or clamp member has been shown for use in connection with wide architraves, the hanger member 40 has been shown as embodying a main body portion 41 having an angular extension or arm 42 formed at its outer end and an oppositely offset bearing portion 43 formed at its inner end. Extending at a right angle from the bearing portion 43 in parallel relation with the main body portion 41 is an arm portion 44 provided at its free end with an anchoring flange 45. The main body portion 41 adjacent its inner end is provided with an opening 46 for rotatably receiving the shank of a headed bolt 47 acting in a like manner as that of the bolts of the coupling means 7 as illustrated in Figure 1. With this form of hanger member, the bearing portion 43 is intended to rest flat upon the face of the architraves 8 to provide a better bearing for the hanger member and also disposing the body portion 41 inwardly of the outer edge of the architraves. As will be observed, the portions 43 and 44 of the hanger member 40 form substantially a hook at the inner end of the body portion 41 for engaging over the outer edges of the architraves to resist movement of the hanger members upon tightening of the bolt 47. As will be observed in Figure 9, the bearing portion 43 of the hanger member and the shank portion 19 of the extensible tie member 6 both have surface contact with the outer face of the architrave 8 and act to prevent tilting of the hanger members and tie member when acting to support a curtain and shade roller respectively.

In both forms of fixtures it will be seen that the tie members and coupling means will be concealed by curtains disposed on the extensible curtain rod, and that the shade roller and curtain rod are supported substantially in a like horizontal plane.

From the foregoing description it will be apparent that a novel and improved combined curtain and shade fixture has been provided embodying a novel arrangement whereby the fixture may be quickly applied to window casings of various widths without

the aid of driven or screw threaded fastening elements, and one embodying a longitudinally adjustable member forming a tie between members adapted to be clamped over the edges of the window casing, and which adjustable member acts to receive shade rollers of various lengths. It will also be apparent that a novel arrangement has been provided whereby the longitudinally adjustable tie member may be shifted transversely of the window casing for properly centering the shade roller over the window opening by proper rotation of the coupling bolts.

Changes in detail may be made to the forms of invention herein shown and described, without departing from the spirit of the invention or the scope of the following claims.

I claim:

1. In a combined curtain and shade fixture, a pair of hanger members, a tie member including bracket arms provided at each end thereof for receiving the trunnions of a shade roller, a bolt extending thru each hanger member and its adjacent bracket arm of the tie member and freely rotatable therein, and a nut disposed inwardly of each bracket arm for threaded reception of said bolts.

2. In a combined curtain and shade fixture, a pair of hanger members for clamping engagement with the outer edges of the side architraves of a window casing, and a longitudinally adjustable tie member arranged between the hanger members with its end portions adapted to engage the face side of said architraves, said tie member including a right angularly offset bracket arm at each end for receiving the trunnions of a shade roller, and a bolt freely rotatable in each hanger member and acting upon the adjacent bracket arm of the tie member for moving the hanger members toward the bracket arms.

3. In a shade support including a pair of hanger members, an elongated hollow coupling section having transversely aligning apertures provided adjacent one end thereof, a minor bracket section including a shank portion extending into one end of the coupling section and a right angled bracket arm for receiving one trunnion of a shade roller, means for fixedly connecting the bracket section to the coupling section, a major bracket section including an elongated shank portion telescopically fitting into the coupling section at the apertured end thereof and a right angled bracket arm for receiving the opposite trunnion of a shade roller, said shank portion of the major bracket section having a series of spaced apart apertures for aligning with the apertures in the coupling section, a removable key extending thru the aligning apertures of the coupling section and shank portion for retaining the major

bracket section in adjusted position, and means for coupling the tie member at its end portions to the hanger members.

4. In a combined curtain and shade fixture the combination of a pair of L-shaped hanger members each having an anchoring flange at the inner end of its longer arm for engaging behind the side of the architrave of a window casing, the anchoring flange of each hanger member parallel to the shorter arm of its respective hanger member and said shorter arms to support a curtain rod, a tie member adapted to support a shade roller, arranged between the hanger members, and threaded coupling means between the terminals of the tie member and the longer arm of each hanger member for forcing said anchoring flanges to positions behind the architraves of the window casing.
